UNITED STATES PATENT OFFICE.

LUIGI VIEZZI, OF NORTH BERGEN, NEW JERSEY, ASSIGNOR OF ONE-HALF TO JOSEPH STILZ, OF WEST NEW YORK, NEW JERSEY.

SPIKE HOLDER AND DRIVER.

Application filed March 21, 1927. Serial No. 177,175.

My invention relates to means for holding a spike after it has been positioned for driving and to means for subsequently driving the spike.

5 The general object of my invention is to provide a mechanism for holding a spike and for driving the same, a more specific object being to provide a spike holding mechanism and a spike driving mechanism 10 so co-ordinated that the spike driving means will function to trip the spike holding mechanism and permit the same to move to a position away from the point of operation 15 of the driving mechanism.

An object also is to provide means for holding the railway tie up to the work of driving the spike.

20 The manner and means whereby the above and other objects are attained will clearly appear as the description proceeds.

Reference is to be had to the accompanying drawings forming a part of this specification, it being understood that the drawings are merely illustrative of one example 25 of the invention.

Figure 1 is a longitudinal vertical section in a plane indicated by the line 1—1 of Figure 2.

Figure 2 is a plan view.

30 Figure 3 is a longitudinal vertical section on the line 3—3 of Figure 2.

Figure 4 is a view similar to Figure 3 showing the spike holding parts in the positions assumed by them after the spike has been released and showing the spike driving parts in positions assumed by them after 35 the driving of the spike.

Figure 5 is a detail in longitudinal vertical section as indicated by the line 5—5 of Figure 7.

40 Figure 6 is a view in the same plane as Figure 5 showing the latch controlling the spike holding means released.

Figure 7 is an end view of the machine.

45 Figure 8 is an enlarged detail as indicated by the line 8—8 in Figure 5.

Figure 9 is a transverse vertical section as indicated by the line 9—9 in Figure 5.

50 Figure 10 is an end view of the machine when employed for driving spikes in a track employing rail chairs, in which event the spike holding means is thrown out of use and the chair relied upon to hold the spike in position to receive the blow of the spike 55 driving means.

In the embodiment of my invention means is provided to grip a railway tie and exert a lifting action thereon to hold the tie to the work of driving and provide for the proper resistance of the spike driving blows. Secondly means is provided to grip the spike and to hold the same in position for being driven; and thirdly, a spike driving mechanism is provided.

60 In carrying out my invention in practice in accordance with the illustrated example, oppositely disposed gripping arms 15 are provided having toothed gripping ends 16, said arms pivoted at their upper ends as at 17 to the short arm of a lever 18 fulcrumed on a pin 19. An angular lever 20 has a handle 21 and is fulcrumed at 123 to one of the arms 15. A link 22 connects lever 20 at the bend thereof by a pivot 23 and pivoted at its other end as at 123 to one arm 15 so 70 that said lever 20 may be caused to open or close the gripping arms 15 on the tie A. The fulcrum pin 19 is movable in a longitudinal slot 24 in a bracket 25 secured to a transverse member 26 on the main truck 80 frame 27, said truck frame having at one side two track wheels 28 in tandem and having a third wheel 29 at the opposite side to engage the other rail. The numeral 30 indicates a toothed rack for holding the 85 lever 18.

On a U-shaped frame element 31 I mount the means for gripping the spike a. Said gripping means includes a pair of gripper arms 32 pivoted at their upper ends as at 132. One arm 32 is formed at its lower end with a curved fork 33 on a gripping head 34. The other arm 32 has a finger 133. A lever 35 is fulcrumed at the lower end 36 and connects by links 37 with the arms 32 so that the rocking of said lever serves to open and close the arms 32 to cause the fork 33 and finger 133 to engage spike a. Lever 35 has a lateral arm 38 to which one end of coil spring 39 is secured, said spring being 90 secured at its other end to a pivot 132 of one arm 32 or adjacent fixed part, so that the spring is expanded when the lever 35 is thrown to a position for gripping the spike to be driven, and upon release of the lever 105 the spring 39 tends to throw the arm 32 to the open position. (Compare Figures 3 and 4). On the latch 134 is an angle member 41 to which one end of a coil spring 42 is secured, the other end of said spring being 110

secured to a member 43 of the frame element 31. The arrangement is such that said spring 42 tends to throw the latch 134 into a latching position. The latch 134 is released from the latching position through the medium of the spike driving means as follows: The spike driving means includes a pneumatic hammer 44 of any approved type, the numeral 45 in Figures 3 and 4 indicating the air hose of said pneumatic hammer. The hammer operates in guides 46 on frame 27. The driving head 47 of hammer 44 is adapted to engage the angle member 41 on latch 134 when the hammer head reaches a certain stage of the driving action so that the arms 32 may be released and be swung by spring 39 to a position away from spike *a* and away from the direct line of the hammer head 47 to afford clearance for the hammer in driving the spike home.

The hammer 44 is fed downwardly as follows: A lever 48 is fulcrumed at one end as at 148 to frame 27 and has an arcuate slot 49 in which moves a lateral pin 50 on hammer 44, the arrangement being such that the downward movement of lever 48 serves to feed the hammer downwardly. The hammer has a handle 51 for manually moving said lever and also has a foot member 52 for the depression of the lever.

With the described arrangement the truck embodying the described mechanisms is brought into a position for the arms 15 to be caused to grip the tie A as in Figure 1. The lever 20 is then operated to close the jaws 15 on the tie A after which the lever 18 is caused to give a lifting action on the arms 15 for holding the tie A up to the work of driving the spike. The lever 35 is now operated to close the arms 32 and spike-engaging members 33 and finger 133 on the spike *a*. While the spike is thus held, lever 48 is operated to feed the hammer 44 to a position to operate on the spike *a* and the driving action of the hammer is continued until the hammer head 47 trips the latch 134 as described, by engaging the member 41 to cause the arms 32 to move away from the path of the hammer, whereupon the downward feed of the hammer is continued until the spike is driven home.

In Figure 10 is illustrated the mode of use of the above described apparatus when a rail chair or seat B is employed beneath the rail, such as C. Said rail seat B is formed with spike holes, one of which is indicated at *b*. In such a case the spike holding assem-

blage including the arms 32 and appurtenances and associated elements are thrown out of action, for which purpose the frame element 31 is pivoted by bolts or screws 53 on which the spike holding assemblage may be arranged to swing when desired. Said frame element 31 is formed with a hole 54 to receive a bolt or screw 55 for tightly fastening the frame element 31 to a bracket arm 56 on the main frame (see Figures 2 and 10).

I would state furthermore that while the illustrated example constitutes a practical embodiment of my invention, I do not limit myself strictly to the exact details herein illustrated, since, manifestly, the same can be considerably varied without departure from the spirit of the invention, as defined in the appended claims.

What is claimed is:

1. In a machine of the class described, spike-holding means comprising swingable arms to engage and disengage the spike, and means on the driving means to engage and displace the spike-holding means.

2. In a machine of the class described, a spike-holding means including swingable gripping arms having means to engage a spike, a lever, and connections between the lever and said gripping arms to cause opening and closing movement of the arms by the operation of the lever.

3. In a machine of the class described, a spike-holding means including swingable gripping means having means to engage a spike, a lever, and connections between the lever and said gripping arms to cause opening and closing movement of the arms by the operation of the lever; together with spring means tending to exert an action on one of the arms to cause opening movement of the arms.

4. In a machine of the class described, a pair of arms pivoted to swing toward or from each other, means on said arms to engage a spike for holding the same while being driven, and latch means to hold the arms in position with the spike engaged thereby.

5. In a machine of the class described, a pair of arms pivoted to swing toward or from each other, means on said arms to engage a spike for holding the same while being driven, and latch means to hold the arms in position with the spike engaged thereby; together with spike-driving means, and means engageable by the spike-driving means for tripping the latch.

LUIGI VIEZZI.
